WRINGER

Thomas W. Behan, Binghamton, N. Y., assignor
to Nineteen Hundred Corporation, Binghamton, N. Y., a corporation of New York

Application February 25, 1932. Serial No. 594,977

5 Claims. (Cl. 68—32)

This invention relates to improvements in clothes wringers and particularly has in view the development of a low, compact form of wringer which is simple in construction and operation, 5 easy to assemble, and readily and quickly thrown into and out of operation.

A feature of the invention is the provision of a single lever which serves to simultaneously apply pressure between the rollers and connect 0 them with the driving mechanism. The same lever is adapted to be readily operated in either direction to effect a quick release of the pressure and a disconnection of the rollers from the driving mechanism. In carrying out this feature of 5 the invention suitable cams are mounted directly upon a shaft which supports one of the rollers and these cams are adapted to connect this roller with certain tensioning devices for creating a desirable pressure between the pair of rollers. 0 In the connection of the rollers with the tensioning devices an increase in the tension of the latter is preferably brought about.

Other features and advantages of the invention will appear from a detailed description 5 which will now be given of a suitable, illustrative form of the same in conjunction with the accompanying drawings in which:

Fig. 1 is a vertical longitudinal section through the illustrative form of wringer.

0 Fig. 2 is a vertical, transverse section along the line 2—2 of Figure 1.

Fig. 3 is a vertical, transverse section along the broken line 3—3 of Figure 1.

Fig. 4 is a vertical, transverse section along the line 4—4 of Figure 1.

Fig. 5 is a side elevational view of the wringer with a portion in section and the cover removed, showing the rollers in ineffective positions, and

0 Fig. 6 is a vertical, transverse section along the line 6—6 of Figure 5.

Referring now to the drawings there may be suitably provided a main frame member 10 having vertically disposed end portions 11 and 12. A gear housing 13 may be formed as an integral 5 part of the frame or as a separate member secured to the frame. In a trough formed in the frame 10 there is mounted a roller 14 which may comprise, for example, an outer cylinder of rubber or similar soft elastic material carried by a metal sleeve 15. At the ends of this sleeve there may suitably be provided bushings 16, formed of brass or similar good bearing material, within which may be mounted a solid shaft 17. This shaft will serve as a stationary support about 10 which the roller will be rotated. At its right end (Figure 1) the shaft may be formed with a flattened portion 18 which fits into a guide groove 19 provided in the frame and rests upon a shoulder 20 of the frame. A similar flattened portion 21 at the opposite end of the shaft fits in a guide

groove 22 in the frame and rests upon a plunger 23 which fits in a socket 24 in the frame and is urged upwardly by a spring 25. Normally this end of the shaft will be elevated into the position shown in Figure 5 but when pressure is applied 65 from above, as will be explained, it will be depressed until it engages a solid portion of the frame, as shown in Figure 1.

Above the roller 14 there is mounted a second substantially similar roller 26 consisting, for example, of rubber surrounding a sleeve 27 having brass bushings 28 or the like within its ends adapted to receive a solid shaft 29. The roller is in this way mounted for free rotation upon the shaft. At each end the shaft is held between guide surfaces formed by the walls of forked projections 30 of bracket members 31. The bottoms of these brackets are formed with lateral projections 32 having threaded openings adapted to receive the upper ends of bolts 33. 75 These bolts pass freely through a shelf portion 34 provided at each end of the frame. Springs 35 surrounding the bolts and compressed between the under surfaces of the shelves 34 and washers 36 at the heads of the bolts normally urge the 80 brackets 31 downwardly until their projections 32 engage the shelves 34. By simply turning the bolts the normal tension on the springs may be varied to suit the particular requirements. At 85 each end of the shaft 29 there is secured a semi-circular cam element 37 having a raceway in its face which approaches the edges of the cam along the substantially diametrical line at which the cam is broken away and approaches the center of rotation at an intermediate point. Each 90 of these cams is adapted to cooperate with a stud or roller 38 carried by the adjacent bracket 31. A handle 39 is attached to one end of the shaft 29 so that the latter may be rotated 95 through an appropriate angle.

It will be apparent that as the shaft 29 is rotated from the position shown in Figs. 5 and 6 to the position shown in Figures 1 and 2 the open end 371 of the cam race will pick up the roller 38 and produce a relative movement between the 100 brackets 31 and the shaft 29. This at first will simply cause the roller 26 to be squeezed against the roller 14, forcing the latter downwardly at its left end until the portion 21 of shaft 17 engages a solid portion of the frame. Subsequently, when downward movement of the roll 26 is 105 sufficiently resisted, the brackets 31 will be raised against the action of the springs 35 which will thus be tensioned to a greater degree. When the cams 37 are in their mid-positions, as shown in Figure 1, the lever 39 will preferably be in a vertical position. A dwell 372 is preferably provided in one or both of the cams so that a definite stopping point may be felt in the movement of the lever into its vertical position. When it is 110

120

desired to release the pressure between the rollers it is simply necessary to force the lever 39 into either of the dotted line positions shown in Figure 3. This permits the release to be effected by 5 the same type of motion from either side. It will be apparent that in applying tension to the upper roller it may be rocked either from the position shown in Figure 6 or from a corresponding position on the opposite side.

10 In the operation of the wringer the lower roller is preferably positively driven and the upper roller is simply driven by friction through contact with the lower roller or with intervening clothes. To permit driving of the lower roller it 15 is provided with a gear 40 secured to the sleeve 15. This gear is adapted to mesh with a gear 41 secured to a horizontal drive shaft 42. When the left end of roller 14 is held in an elevated position, as shown in Figure 5, the teeth of gear 40 20 will be out of mesh with those of gear 41 but when tension is applied to the upper roller in the manner explained and the end of roller 14 is rocked downwardly the two gears will be brought into mesh. At its opposite end the shaft 42 carries a bevel gear 43 which is constantly in mesh 25 with bevel pinions 44 and 45 loosely mounted on a shaft 46. The lower end of this shaft is provided with pins or projections 47 to permit it to be readily connected with a power driving 30 source. A clutch element 48 is splined to the shaft to permit it to slide longitudinally along the shaft and be rotated thereby. It may be placed in its lower position in which projections 35 49 engage recesses in the pinion 45, or it may be held in its upper position in which upper projections 49 engage recesses in the pinion 44, or it may be held in an intermediate, neutral position. For the purpose of shifting the clutch element to determine the direction of rotation of 40 the rollers it may be provided with a groove around its entire periphery adapted to receive a pin 50 mounted eccentrically with relation to a shaft 51. At its outer end this shaft may carry a lever 52 adapted to be adjusted into any one of 45 three positions, 90° apart, corresponding with the three positions of the clutch element previously explained.

Water which is removed from the clothes in the 50 operation of the wringer is collected in a trough beneath the lower roller and is discharged through an opening 53 into a chute or channel member 54 which may be secured to the underside of the frame 10 and extend downwardly at a small angle toward both sides of the wringer. A deflector 55 beneath the opening 53 may serve to direct the water to one side or the other. This deflector may suitably be pivoted as shown and may be connected by a shaft 56 with a shaft 57 mounted in an opening through the shaft 42. The inner end 60 of the shaft 57 may carry an arm having a projection adapted to ride in the groove in the periphery of the element 48. In this way the deflector will be adjusted in response to the shifting of the clutch to determine the direction of rotation of the rollers. The arrangement may appropriately be such that as the rollers are rotated to draw clothes from one side of the wringer the water will be deflected toward the same side.

70 Suitable means may be included for latching the wringer frame in any position to which it may be swung about the vertical axis 59. For this purpose a plunger 60 urged downwardly by a spring 61 within a socket in the gear housing may

cooperate in well known manner with recesses or openings in the top of the supporting structure. A bell crank lever 62 (Figure 5) carrying a pin 63 80 may be rocked to lift the plunger and disengage it from a recess, thus permitting the entire wringer frame to be swung laterally. A cover member 64 may be placed over the upper roller, having a telescopic fit with the upright portions 11 and 12 of the frame. This cover may be simply loosely applied or latched in any suitable way, as desired.

85 While an illustrative form of the invention has been disclosed in considerable detail it will be understood that various changes may be made in the form, construction and arrangement of the several parts without departing from the general spirit and scope of the invention as defined by the claims.

90 I claim:

95 1. In a wringer a frame, a pair of rollers mounted in said frame, a shaft supporting one of said rollers, tensioning means carried by said frame, cams secured to said shaft and adapted to engage said tensioning means to connect the latter with said shaft, and a lever for operating said cams, said lever being rockable in either direction from 100 an intermediate position to effect release of said tensioning means from said shaft.

105 2. In a wringer a frame, a pair of rollers mounted in said frame, a shaft supporting one of said rollers, tensioning means carried by said frame, 105 projections on said tensioning means, a cam secured to each end of said shaft engageable with one of said projections to connect the tensioning means with the shaft, and a lever secured to the shaft for operating said cams.

110 3. In a wringer a frame, a pair of rollers mounted in said frame, a shaft supporting one of said rollers, tensioning means carried by said frame, projections on said tensioning means, a cam secured to each end of said shaft engageable with 115 one of said projections to connect the tensioning means with the shaft, a dwell at an intermediate point in one of said cams adapted to receive one of said projections when said tensioning means is properly connected with the shaft, and a lever 120 secured to the shaft for operating said cams, said lever being rockable to either side from an intermediate position to release said tensioning means.

125 4. In a wringer a frame, a pair of rollers mounted in said frame, operating means including a driving gear, a driven gear carried by one of said rollers and adapted to mesh with said driving gear, means normally holding said gears out of mesh, tensioning means carried by said frame, 130 cams adapted to connect said tensioning means with the other of said rollers, and a lever for operating said cams, said gears being automatically brought into mesh upon operation of said lever to connect said tensioning means and roller.

135 5. In a wringer a frame, a pair of rollers mounted in said frame, operating means including a driving gear, a driven gear carried by one of said rollers and adapted to mesh with said driving gear, means normally holding said gears out of mesh, tensioning means carried by said frame, a 140 shaft supporting the other of said rollers, cams carried by said shaft adapted to connect the latter with said tensioning means, and a lever carried by said shaft for operating said cams, said gears being automatically brought into mesh upon operation of said lever to connect said tensioning means and roller.

THOMAS W. BEHAN.
